INVENTOR

Victor J. Evans

ATTORNEY

UNITED STATES PATENT OFFICE

ANTHONY F. KUKULSKI, OF PHILADELPHIA, PENNSYLVANIA

SANITARY SINK RACK

Application filed September 14, 1928. Serial No. 306,029.

This invention relates to racks or other supporting devices adapted for use within sinks and other receptacles.

An object of the invention comprehends a multiplicity of supporting members.

Another object of the invention contemplates cross members adapted for connection with the supporting members to provide a grating.

10 An additional object of the invention consists in the provision of bosses upon the supporting members to dispose the completed rack in an elevated position.

More specifically stated the joints or inter-
15 sections between the supporting members and cross members are rounded to prevent adhering of foreign matter to obviate premature deterioration of the rack.

With the above and other objects in view,
20 the invention further consists in the following novel features and details of construction, to be hereinafter more fully described, illustrated in the accompanying drawing and pointed out in the appended claim.

25 In the drawing:—

Figure 1 is a perspective view of the completed invention.

Figure 2 is a horizontal sectional view taken through the invention as applied for
30 use within a sink.

Figure 3 is a fragmentary perspective view of a modified form of my invention.

Referring to the drawing in detail, wherein like characters of reference denote corre-
35 sponding parts, the reference character 10 indicates an elongated frame or supporting member preferably constructed in one piece and having rounded ends 11.

Rails 12, arranged in spaced parallel relation within a frame 10, are adapted for connection at their ends with the inner sides of the end rails of the frame.

40 Projections 13, carried upon the outer side walls of the end and side rails of the frame 10 and through spaced openings therein, are adapted to simulate the ends of the rails whereas in fact the entire grating is constructed in one piece. The points of intersection between the ends of the rails 12 and
50 the end walls of the frame and the projec-

tions 13 therewith are rounded, as indicated at 14, to prevent crevices within which extraneous matter may find its way and render the rack exceptionally hard to clean.

From the illustration in Figure 1 of the drawing, it is noted that the thickness of the frame is greater than that of the rails 12 whereby the latter will be elevated from the body of the sink, substantially as illustrated in Figure 2 of the drawing. Such arrangement will permit drainage of dishes or other receptacles within sinks toward the drain, usually located in the center of the sink.

Semi-circular groove portions 15, horizontally disposed in the upper and lower side edges of the frame 10, will permit drainage from the out side of the frame toward the sink drain or cesspool.

The improved grating is preferably constructed of bakelite, hard rubber or other rust proof material and treated to obviate inflammation incident to the heat of vessels placed thereon. By reason of the fact that the grooves 15 are arranged both in the bottoms and tops of the side rails for the frame, the latter may be turned upon either side within a sink or receptacle. The additional thickness of the frame will also facilitate application of the rack within sinks or other receptacles having uneven bottoms.

Rounding the ends of the frame and the intersections of the rails 12 therewith will obviate accumulation of grease and other foreign matter whereby rust or other deterioration will be obviated and cleaning made easier.

If desired, projections 15' may be disposed upon the rounded ends of the frame to elevate the entire rack from the bottom of the sink or other receptacle whereby the latter may be most effectively drained.

The invention is susceptible of various changes in its form, proportions and minor details of construction, and the right is here-
55 in reserved to make such changes as properly fall within the scope of the appended claim.

Having thus described the invention, what is claimed is:—

A rack comprising an elongated frame having rounded ends, rails of relatively narrow
100

depth disposed in spaced parallelism with the frame and having connection at their ends with the end walls of the frame, projections included upon the outer sides of the walls of the frame to simulate the ends of the rails projecting through the adjacent portions of the frame, projections carried by and extended from the rounded ends of the frame to elevate the rack and permit drainage therebeneath, and the side walls of the frame having semi-circular grooves in the opposed side edges thereof for coaction with the adjacent projections at the rounded ends of the frame.

10   15   In testimony whereof I affix my signature.

ANTHONY F. KUKULSKI.
